UNITED STATES PATENT OFFICE.

CHESTER E. WARNER, OF BERWYN, ILLINOIS, ASSIGNOR TO BENJAMIN ELECTRIC MANUFACTURING COMPANY, OF CHICAGO, ILLINOIS, A CORPORATION OF ILLINOIS.

ELECTRICAL SWITCH.

Application filed November 24, 1919, Serial No. 340,337. Renewed May 9, 1925.

To all whom it may concern:

Be it known that I, CHESTER E. WARNER, a citizen of the United States, residing at Berwyn, in the county of Cook and State of Illinois, have invented new and useful Improvements in Electrical Switches, of which the following is a full, clear, concise, and exact description, reference being had to the accompanying drawing, forming a part of this specification.

My invention relates to electrical switches and more specifically to pull switch sockets.

One of the objects of my invention is to provide an improved switch construction in which the circuit is simultaneously broken at two points, whereby the arcing effect is divided and the danger of injury to the switch is lessened.

Another object of my invention is to provide a switch construction wherein the switch mechanism is mounted for most efficient operation and to form a neat and compact arrangement of parts.

Further objects will appear from the detailed description to follow and from the appended claims.

In the drawings in which one embodiment of my invention is shown—

Fig. 1 is a plan view of a pull switch socket embodying my invention, the cap being removed;

Fig. 2 is a section substantially on the line 2—2 of Fig. 3;

Fig. 3 is a section substantially on the line 3—3 of Fig. 1;

Fig. 4 is a section substantially on the line 4—4 of Fig. 1;

Fig. 5 is a section substantially on the line 5—5 of Fig. 1;

Fig. 6 is a detail perspective view of the pawl member used to rotate the contact carrier;

Fig. 7 is a perspective view of the disc and contact carrier; and

Fig. 8 is a detail perspective view of the movable contact member.

In order to give a general idea of the invention, it is here stated that the embodiment of my invention here shown comprises a pull switch socket having a pair of rotatably mounted contacts 10 and 11 (which, however, are always electrically connected with each other), a pair of spring contact fingers 12 and 13 (insulated from each other in the "off" position of the switch and with

respect to which the rotatably mounted contacts 10 and 11 respectively snap into and out of engagement in their rotation), wiring terminals 14 and 15 (the wiring terminal 14 being electrically connected with the spring contact finger 12 and the wiring terminal 15 being electrically connected with the threaded shell contact 16 of the receptacle), a center contact 17 for the receptacle electrically connected with the spring contact finger 18, an insulating base 18 on which the receptacle contacts, wiring terminals and switch mechanism are mounted, and a sheet metal casing 19 for housing the insulating base 18 and the parts supported thereby.

From the construction described, it will be seen that the spring contact fingers 12 and 13 are insulated from each other in the "off" position of the switch; that the spring contact finger 12 is always electrically connected with the wiring terminal 14 and that the spring contact finger 13 is always electrically connected with the center contact 17. It will also be seen that as the movable contacts 10 and 11 are rotated, the circuit between the wiring terminal 14 and center contact 17 will be simultaneously broken at two points, thereby dividing the arc and lessening the danger to the switch mechanism and preventing other undesirable effects.

Referring to the construction in detail, the switch mechanism is located in recesses 20 in the insulating base 18. This switch mechanism comprises in addition to the rotatably mounted contacts 10 and 11 and the cooperating spring contact fingers 12 and 13, previously described, a rotatably mounted contact carrier 21 of insulating material, an oscillatable pawl member 22 forming a switch lever, having a ratchet connection with the contact carrier 21, and the coil torsion spring 24 for returning the pawl member 22 after it has been operated by the pull chain 25. A switch shaft 26 supports the spring 24, the pawl member 22 and the contact carrier 21 and is suitably supported in the offset recess portions 20a.

The contact carrier 21 comprises a ratchet shaped portion 27 on which the contacts 10 and 11 are mounted and a central web 28 having notches 29 therein. The contact members 10 and 11 may be formed as integral parts of a curved sheet metal stamping 30, and are thus permanently electrically 110

connected. The curved contact plate 30 is provided with projections 31 thereon to engage in the notches 29 in the central web 28 of the contact carrier, and thus anchor the plate 30 in place. The plate 30 has integrally formed inwardly extending projections 32 thereon which engage in corresponding recesses 33 in the contact carrier to further assist in this anchoring. The contact plate 30 may be secured to the carrier by first inserting the projections 32 into the receiving recesses 33 and springing the plate 30 so that the projections 31 engage the notches 29 in the central web 28.

15 The contact carrier 21 has in operative connection therewith a disc member 34, this disc member and contact carrier being both composed of some suitable insulating material. Said disc constitutes a flange extending beyond the periphery of said carrier, this flange acting as an insulating barrier between the conducting and operating parts of the switch mechanism.

The contact carrier and disc are revolved by means of the pawl member 22 which may be actuated in any desired manner. In the specific embodiment illustrated, the pawl member comprises a metallic disc 35 fitted with a bifurcated hook member 36 adapted to receive the chain 25. The disc 35 has a central web portion 37 integrally formed therewith which has a central opening 38 therein whereby the pawl member may be loosely mounted on the switch shaft 26. The pawl member 22 is fitted with the projecting pawls 39 and 40 which pawls in the assembly of the switch mechanism are placed adjacent the face 41 of the disc 34. The pawl member 22 also has outwardly projecting prongs 42 and 43 which project from the opposite face of the disc from which the pawls 39 and 40 extend. The pawl member 22 has integral arcuate portions 44 and 45 which together constitute a chain rail for the chain 25. The pawl member is preferably made from one piece of material punched and formed into the construction illustrated in Fig. 6.

Either one of the prongs 42 or 43 can be utilized to secure one end of the spiral spring 24 to the pawl member 22, the spring 24 being concentrically disposed with respect to the switch shaft 26 and having the offset end thereof secured to the ledge 46 provided for this purpose in the insulating base 18. Consequently, when the chain 25 is operated, it will carry with it the pawl member 22 which, in turn, will tension the spiral spring 24. The movement of the pawl member 22 is limited by a projection 47 located in the path of said member (Fig. 5). The forward movement of said pawl member under the action of the chain 25 will be limited by the engagement of the forward edge 48 of said member with the projection 47 and

the return movement of said member will be limited by the engagement of the hook 36 with said projection 47.

The face of the contact carrier is equipped with lugs 49 and 50 which cooperate with the notches 51 and 52 of the disc 34. When the disc 34 is assembled with relation to the contact carrier 22, in which position the notches 51 and 52 receive the lugs 49 and 50 respectively, the construction is such that the thickness of the plate or disc 34 is the same as the highest point 53 (Fig. 7) of the lugs 49 and 50 respectively. It is evident, therefore, that when the disc and contact carrier are assembled due to the tapered construction of the lugs 49 and 50 that the notched portions 51 and 52 will also be accessible to the pawls 39 and 40 of the pawl member 22 whereby these three members 21, 34 and 22 may be simultaneously operated. The spring 24 serves the double function of returning the pawl member 22 after it has been operated by the pull chain and of exerting an expansive force whereby the pawl member 22 is held snugly in position against the face 41 of the disc 34.

The central web 28 of the contact carrier, serves not only to provide securing means for the contacts, but also provides an insulating barrier between the ends of the contact springs 12 and 13 at the time of the break and thereby prevents arcing between them.

As previously stated, the spring contact finger 13 is always in electrical connection with the center contact 17, this connection being effected by means of a screw 54 which also serves to hold this spring contact finger and the center contact in place on the base 18.

The wiring terminal 14, as previously stated, is electrically connected with the spring contact finger 12, this wiring terminal being held in position on the base 18 and in engagement with the spring contact finger 12 by means of a screw 55. Each of the wiring terminals 14 and 15 is provided with the usual binding screw 56, the wiring terminal 15 being electrically connected with the threaded shell contact 16 of the receptacle by means of a screw 57 (Fig. 2) which engages the flange 58 of the threaded shell contact.

The circuit from the wiring terminal 14 to the wiring terminal 15 has been outlined in connection with the description of the construction and is as follows: From the wiring terminal 14 through the spring contact finger 12, the contact 10, the curved plate 30 (which is integrally formed with the contacts 10 and 11) the contact 11, the spring contact finger 13, the screw 54 to the center contact 17 through whatever translating device is inserted in the receptacle to the threaded shell contact 16 and thence

through the screw 57 to the wiring terminal 15.

As previously stated, when the switch is moved to "off" position, the circuit is simultaneously broken at two points between the center contact and the wiring terminal thus dividing the arc.

The operation of my improved switch is as follows: Assuming that the parts are in the position shown in Fig. 4 (in which the switch is in "off" position) and it is desired to turn the switch "on," the pull chain 25 is pulled down to move the pawl member through substantially 180 degrees. During this movement of the pawl member through 180 degrees, the contact carrier 21 also is moved through 180 degrees due to its ratchet connection with the pawl member. During this movement of the contact carrier 21, the spring contact fingers 12 and 13 ride upon the non-conducting cam portions 27 of the contact carrier and finally snap down into engagement with the curved contact plate. This simultaneously makes the circuit between the center contact and wiring terminal at two points.

When the pull chain 25 is released, the spring 24 returns the pawl member to its original position, the contact carrier, however, remaining stationary during this return movement of the pawl member and pull chain, the ratchet connection between the pawl member and contact carrier permitting this return movement. The spring contact fingers 13 and 14 would prevent any return movement of the contact carrier by their engagement with the shoulders behind which they have just snapped. If now it is desired to turn the switch "off," the pull chain 25 is again operated, again causing the contact carrier 21 to be moved through 180 degrees. During this movement of the contact carrier 21, the spring contact fingers 13 and 14 ride upon the curved contact plate 30 and upon the contacts 10 and 11, and finally snap off from the rear of these contacts; this breaks the circuit simultaneously at two points between the center contact and its wiring terminal and divides the arc.

When the pull chain 25 is released, it and the switch lever are again restored to their original positions by means of the spring 24, the contact carrier 21 remaining stationary during this return movement, the spring contact fingers 13 and 14 again preventing any return movement of the contact carrier by engagement with the shoulders behind which they have just slipped.

As clearly illustrated in the drawings, the combination disc and contact carrier is positioned with its rotating axis transverse to the axis of the socket and to the direction of pull of the chain; consequently the chain 25 may be so positioned, as illustrated in Fig.

5, that the pulling force exerted thereon is communicated to the carrier 21 in a direct line without the necessity of moving the chain through any curves or angles which is ordinarily necessary when the axis of rotation of the disc and contact carrier is placed in the position substantially parallel to the axis of the socket. With this construction a direct tangential pull is obtained. Further, since the contact carrier is provided with but two cam surfaces and two teeth or shoulders, a comparatively small disc can be utilized and a good, long, smooth, positive pull will be obtained at the chain for the operation of the switch mechanism. Because of the use of two cam surfaces, each substantially 180 degrees in length, a long, smooth pull on the chain is obtained, notwithstanding the use of a contact carrier of small diameter, which obviously results in a positive and smooth action of the switch mechanism.

Obviously the invention is not limited to the specific embodiment thereof herein illustrated and described, but is capable of many variations and other applications within the spirit and scope of the invention as set forth in the following claims.

Having thus described my invention, what I claim as new and desire to secure by Letters Patent is:

1. A switch socket having a receivable contact, a wiring terminal and means for establishing electrical connection between said receptacle contact and said wiring terminal, said means comprising a rotatably mounted insulating carrier having cams terminating in abrupt drops, contact plate carried by said carrier and covering one of the cams thereof, said plate having a pair of contact extensions, the carrier having a radially projecting barrier extending therefrom between said extensions, a spring contact finger electrically connected to said receptacle contact, a second spring contact finger electrically connected to said wiring terminal, both of said spring contact fingers being arranged to ride on said curved contact plate and to snap off its said extensions, said barrier being disposed to pass in between said contact fingers before said fingers leave said contacts and to separate said fingers when the latter snap off said extensions.

2. A switch socket having a wiring terminal, a receptacle contact and means for establishing electrical connection between said wiring terminal and said receptacle contact, said means comprising an insulating contact carrier mounted to rotate and having two cams of 180 degrees each, each cam terminating in a drop, a curved contact plate secured on said contact carrier and covering one of said cams, said contact plate having two contact extensions

thereon, a pair of contact fingers, one of said contact fingers being electrically connected to the wiring terminal, the other being electrically connected to the receptacle contact, said fingers being arranged to drop simultaneously upon said curved contact plate and to drop simultaneously off the same at the ends of the contact extensions, and an insulating barrier on the contact carrier so located with relation to the contact extensions as to separate the same and also to separate the contact fingers from each other when the latter drop off the ends of the contact extensions.

15 3. A switch socket having a wiring terminal and a receptacle contact and means for establishing electrical connection between said wiring terminal and said receptable contact, said means comprising a rotatably mounted insulating contact carrier, means for advancing said carrier with a step by step movement through 180 degrees upon each actuation of the switch, said carrier having a fin-like insulating barrier extending radially therefrom, and extending only partially around said carrier, a curved contact plate secured to said contact carrier and terminating in two contact extensions, said curved contact plate being so located on said carrier that said barrier projects between said extensions, and a pair of stationary contacts, one of which is electrically connected to said wiring terminal and an-

other to the receptacle contact, and arranged to lie upon opposite sides of said insulating barrier when said contacts leave said curved contact plate.

4. A pull switch mechanism for effecting a double break in series comprising a rotatable commutator, a pull member, means whereby each pull on said pull member will cause the commutator to rotate substantially 180 degrees, said commutator comprising a pair of spaced conducting cam portions and a pair of insulating cam portions, a pair of contacts co-operating with said cams, each contact being alternatively engageable with a conducting cam and a non-conducting cam, and means rotatable with said commutator for electrically connecting said spaced conducting cams.

5. A switch mechanism comprising a rotatable commutator provided with a bifurcated contact member, with an insulating barrier between said bifurcations, said bifurcations extending circumferentially alongside each other and being spaced from each other along the axis of the commutator, and a pair of spaced contacts co-operating with said bifurcations respectively, said barrier being movable in the space between said contacts.

In witness whereof, I have hereunto subscribed my name.

CHESTER E. WARNER.
